(57) **CLAIM**

The ornamental design for a feather duster holder vacuum cleaner accessory, as shown and described.

DESCRIPTION

FIG. 1 is a perspective view of a feather duster holder vacuum cleaner accessory showing my new design without the feather duster;

FIG. 2 is a left side elevation view thereof;

FIG. 3 is a top plan view thereof;

FIG. 4 is a rear elevation view thereof;

FIG. 5 is a right side elevation view thereof;

FIG. 6 is a front elevation view thereof;

FIG. 7 is a bottom plan view thereof;

FIG. 8 is a top plan view of a feather duster;

FIG. 9 is a rear elevation view thereof;

FIG. 10 is a front elevation view thereof;

FIG. 11 is a left side elevation view thereof, the right side being a mirror image thereof;

FIG. 12 is a perspective view of a feather duster holder vacuum cleaner accessory in assembled condition;

FIG. 13 is a left side elevation view thereof;

FIG. 14 is a top plan view thereof;

FIG. 15 is a rear elevation view thereof;

FIG. 16 is a right elevation view thereof;

FIG. 17 is a front elevation view thereof; and,

FIG. 18 is a bottom elevation view thereof.

The claim is directed to the feather duster holder vacuum cleaner accessory shown in FIGS. 12-18. FIGS. 1-11 are shown separate for clarity of illustration.
